IRONING TABLE

Oscar A. Flagstad, Minneapolis, Minn.

Application November 2, 1931, Serial No. 572,487

15 Claims. (Cl. 68—10)

This invention relates to collapsible ironing tables, and the primary object is to provide such a table that is comparatively simple, efficient, and practical in design, that is exceptionally firm or rigid when set up and in use, and which collapses in such a manner as to take up but a very small amount of floor space when it is folded together and out of use. A further object is to provide a collapsible ironing table in which the collapsing frame work is so designed that the table can be set up or taken down with a minimum amount of physical effort, and wherein said operations can be effected without the necessity of the operator stooping over or stretching to manipulate the various parts. These and still other and more specific objects will be disclosed in detail in the course of the following specification, reference being had to the accompanying drawings, wherein:

20 Fig. 1 is a perspective elevation of an ironing table incorporating a preferred embodiment of the invention.

Fig. 2 is a perspective view similar to Fig. 1, but showing the table in a partly collapsed condition.

Fig. 3 is an enlarged detail sectional elevation as seen about as on the line 3—3 in Fig. 1.

Fig. 4 is a sectional detail view on the line 4—4 in Fig. 3.

Fig. 5 is a perspective elevation of the table showing it as entirely collapsed or folded together as when it is to be set away out of use.

Fig. 6 is a perspective detail view of a spring hook device, as seen on the line 6—6 in Fig. 5.

Fig. 7 is an enlarged detail section through a latch mechanism, as seen on the line 7—7 in Fig. 5.

Fig. 8 is a perspective elevation similar to the lower part of Fig. 1, but showing a modified form of bracing structure.

Fig. 9 is a perspective elevation of an ironing table embodying a form of the invention that is somewhat modified from those shown in Figs. 1 to 7, and in Fig. 8.

Figs. 10 and 13 are detail perspective views showing modified forms of brace construction.

Fig. 11 is a perspective elevation of a metal ironing board, detached from the leg and brace structure, this unit having certain novel features of construction which of course are not present in the wooden type for which it may be readily substituted.

Fig. 12 is an enlarged sectional detail view on the line 12—12 in Fig. 11.

Reference will now be made to the various figures of the drawings by reference characters, like

parts being designated by like characters in the particular figures wherein such parts are shown. It may here be noted that as a matter of convenience the terms "board" or "ironing board" will be used in its popular sense to indicate broadly the 60 flat element presenting the ironing surface, and regardless as to whether said "board" is strictly a wooden board, or is made of sheet metal or other material; and, the terms "table" or "ironing table" will be employed in the broad sense of including 65 both the "board" and also the supporting structure which is made up of the legs, braces, and other collapsible elements.

In the embodiment of the invention illustrated by Figs. 1, 2, 3, 4, 5, 6, and 7, the ironing table is 70 made up, essentially, of the ironing board A, a rear supporting leg frame B, a forward or front leg frame C, a connecting frame D rigidly connecting lower portions of the respective leg frames B and C, and a brace frame E detachably connecting the 75 rear end of the board A to a lower part of the leg frame B to rigidly maintain the board in a horizontal position and also to releasably lock the leg connecting frame D with respect to the leg frame B.

The ironing board A proper as shown is made of wood and is provided upon its under side with a transverse cleat 14 and a pair of converging brace members 15 all of which are designed to reinforce the board and resist any tendency to 85 warping and distortion. The board is further provided with a metallic cross strap 16 having depending ears 17 at its opposite ends to which the leg frames B and C are pivoted as by rivets 18.

The leg frame B is made up of a pair of parallel angle iron legs 19 and 20, which are connected by a cross bar 21. This cross bar is secured to the rear flanges of the legs as by rivets 22, while angular end extensions 23 of the bar, are bent around parallel with but slightly spaced from the lateral flanges of the legs 19—20, as shown in Fig. 4, so as to engage the rivet heads 24 of arm extensions 25 at the ends of the metal rod, which forms the brace frame E, and thus prevent 95 said extensions 25 from slipping or moving laterally out of place in the legs. The frame E, as already indicated is preferably made of bar or rod iron, and is substantially V-shaped except for the extensions 25, and a short cross piece 26 at 105 its apex or upper end.

The cross arm 26 of the frame E is designed for quickly releasable interlocking engagement with a lock or latch device G secured upon the underside of the rear end of the board A. This device 110

G comprises a sheet metal bracket or housing 27, rigidly secured to the board and having a notch or slot 28 to receive the cross piece 26 of the brace E. As pressure upon either end of the board A results in longitudinal stresses in the brace frame E, the slot 28, as shown particularly in Fig. 7, is disposed at right angles to the plane of the frame, with a result that the stresses in question will be imparted directly to the member 27 and they will have no tendency to pull the cross piece 26 out of the slot 28. The said cross piece 26 is releasably secured in place by an unbalanced latch member 29, which is pivoted in the bracket 27, as at 30, and has a relatively heavier inner end arranged to drop into the position shown in Fig. 7 to hold the bar 26 from dropping out of the notch 28. To remove the bar 26 it is only necessary for the operator to engage the outer or exposed end of the lever 29 and tilt it to the dotted line position (Fig. 7), thus permitting the brace to drop out of engagement with the member 27. It may here also be noted that the lever 29 is so arranged that moving the brace piece 26 into the recess 28 automatically raises the lever and thus snaps the brace into locked position without any other effort on the part of the operator.

The board A is provided on its under surface with a second releasable securing device, H, as shown in Figs. 2, 5, and 6, and this device has for its purpose to secure the various collapsible parts of the table in their folded or nested positions so that the table can be handled and stored or set away as a compact unit, and without any danger that some of the sections or parts thereof will drop or move out of place. This device H, as shown, consists primarily of a flanged base plate 31, to which an L-shaped hook member 32 is pivoted as at 33, for releasable engagement with the cross bar 21 of the section or frame B. A spring 34 is arranged to releasably hold the hook in engagement over the bar.

The leg frame C as previously indicated is pivoted to the board A as at 18, and is made up of two inclined angle iron legs 35 and 36 which are rigidly connected near their lower ends by a cross bar 37 and braces 38.

The connecting frame D is substantially U-shaped in form with its ends pivotally connected to the frame C as at 39. This frame D is made of a single bar or rod of iron, and the cross bar 40 forming its rear end is offset downwardly as indicated in Figs. 2 and 3, so that it may drop down between the rearwardly offset portion of the cross bar 21 and the lateral arm extensions 25 of the brace frame E, thus forming a rigid interlocking connection between the frame D and the frames B and E. It will of course be noted that the rear end of the frame D encloses the frame E so that the bar 40 may drop down into the position indicated. It may also be noted with particular reference to Figs. 3 and 4 that after the frame D has been dropped down into its operative position and the frame E is moved rearwardly for interlocking engagement with the latch G, the side bars of the frame E will be moved into a rearwardly inclined position where they will effectively hold the cross bar 40 down in its proper position, and will thus prevent the frame D from being moved out of place while the table is in use. It may here be noted that the only substantial difference between the structure shown in Figs. 1, 2, and 5 and that shown in Fig. 8, is that the first noted figures show the frame D as being of a rectangular shape while the frame

D1 as shown in Fig. 8 illustrates a connecting structure in which the two frame bars are crossed so as to have better bracing effect as between diagonally opposed table legs which may be found preferable under certain circumstances.

When it is desired to convert the table from its set up position, as shown in Fig. 1, to the fully collapsed position shown in Fig. 5, the operator first engages the rear end of the latch lever 29 to thereby release the cross piece 26 of the frame E. The forward end of the board A can then be dropped down into the position indicated in Fig. 2. The upper or rear end of the board may then be lifted slightly until the operator can conveniently grasp the bar 40 of the frame D, whereupon the latter can be lifted toward the board while the frames B and E are folded under and upwardly toward the now lowered end of the board, the entire device of course being now supported only by the leg frame C. As the various parts are moved into their collapsed position, as shown particularly in Fig. 5, the operator engages the hook 32 and moves it down until it can be engaged over the cross bar 21 of the frame B to rigidly secure all the parts in their folded positions as previously noted.

In the modified structure shown in Fig. 9 I have illustrated how the invention may be incorporated in a table having only three bearing points upon the floor, as is sometimes found desirable. In this instance the board A, the leg frame B, and the bracing frame E are all substantially identical with the parts bearing the same characters in the previously described figures, except, however, that the legs 41 and 42 of the frame B are channel shaped in cross section in preference to the angle iron structure of the previously described legs 19 and 20. In this instance the forwardly disposed leg frame C1, instead of being of the angle iron type shown in Fig. 1, is made up of a single piece of comparatively heavy bar iron, the same being substantially V-shaped in form and with its upper ends pivotally connected to board A as at 43. The lower end of the frame C1 in this particular instance is provided with a short cross piece 44 which extends through eyes 45 formed at the forward converging ends of the bar which forms the triangular connecting frame D1, which is of course substituted for the previously described frame D of Fig. 1. It will of course be understood that the eyes 45 at the forward end of the frame D1 rotatably engage the cross piece 44 of the frame C1 and provide the actual floor contacting foot for the forward end of the leg frame C1.

In the modification shown in Fig. 13 the eyes 45 of Fig. 9 have been substituted by a sheet metal member 46 having a bearing portion 47 for bearing engagement with the cross piece 44. This member 46 is doubled back upon itself at its rear to form a pair of receiving pockets or openings for the forward ends of the bars 48, which make up the now slightly modified connecting frame D2, and as these rod ends are put in place within the member 46 they are rigidly and permanently secured thereto by spot welding, which operation also of course firmly unites the two adjacent portions of the member 46.

In the modification shown in Fig. 10, the forward leg frame C2 is made up of a single piece of bar metal, the lower end of which is doubled upon itself and bent around to form a floor contacting shoe as well as a bearing 49 for the reception of a cross piece 50 of a triangular bracing frame D3. In this instance also the upper ends

of the bar forming the frame C2 are provided with laterally projecting ends 51 adapted to serve as pivots for the frame as well as for the rear leg frame B.

5. The metal ironing board unit A1, shown in Figs. 11 and 12, comprises a flat elongated piece of sheet metal having a depending curved flange 52 extending integrally therefrom and about its entire edge, which flange of course constitutes a substantial reinforcing and rigidifying medium. To further resist any flexing or bending tendency in the board I provide it with a reinforcing frame 53. This frame is made up of an endless piece of comparatively heavy strap iron, and is designed with an irregular shape so that certain parts of it will contact at spaced intervals with the flange 52, and at which intervals it will be spot welded to the flange as at 54, while intermediate parts of the frame 53 will extend in under 10 the plate proper, as at 55, to give the desired support and bracing effect. At spaced intervals the frame 53 is further secured by cross bars 56 and 57, which are riveted or otherwise fastened as shown, and the latter of which may have the end 25 lugs 58 for connecting the leg frames of the table. The cross bars 56 and 57 have depending loops 59 for engaging and securing adjacent parts of the frame 53.

It is understood that suitable modifications may 30 be made in the structure as disclosed, provided such modifications come within the spirit and scope of the appended claims. Having now therefore fully illustrated and described my invention, what I claim to be new and desire to protect by 35 Letters Patent is:

1. The combination including an ironing board, front and rear leg frames pivotally connected to the board to form a support therefor at a point intermediate the ends of the board, a connector 40 frame extending from the front leg frame for bracing engagement with the rear leg frame, and a second bracing frame pivotally secured at its lower end to and extending from the rear leg in substantial parallelism with the front leg 45 frame, and to one end of the board for supporting the board in a horizontal position, said second bracing frame cooperating with the rear leg frame to form an interlock, adjacent the point of pivoted connection therebetween, to releasably secure the connector frame in its said bracing 50 engagement with the rear leg frame.

2. In a collapsible ironing table the combination comprising an ironing board, a substantially upright rear leg frame disposed under a rear 55 portion of the board and hingedly secured thereto, a second leg frame disposed in an inclined position under the forward part of the board, a connector frame pivotally attached at its forward end to the inclined leg frame and having a cross bar at its rear for releasable engagement with said first mentioned leg frame, and a brace frame disposed in substantial parallelism with the second leg frame for connecting said rear leg frame to the board and releasably engaging the cross 60 bar of the connector frame to lock the same with respect to said rear leg frame.

3. The combination including an ironing board, front and rear leg frames pivotally connected to the board to form a support therefor, a connector frame extending from the forward leg frame rearwardly and having a cross bar at 70 its rear end for interlocking connection with the rear leg frame, and a brace frame extending from the rear leg frame upwardly and rearwardly to

the board but in front of said cross bar to establish said interlocking connection.

4. The combination including an ironing board, front and rear leg frames pivotally connected to the board to form a support therefor, a connector frame extending from the forward leg frame rearwardly and having a cross bar at its rear end for interlocking connection with the rear leg frame, and a brace frame extending from the rear leg frame upwardly and rearwardly to the board but in front of said cross bar to establish said interlocking connection, said rear leg frame having means for abutting against the rear end of the connector frame.

5. The combination including an ironing board, front and rear leg frames pivotally connected to the board to form a support therefor, a brace frame for bracing the board with respect to one of the leg frames, and a connector frame between the leg frames, said brace frame comprising a substantially V-shaped bar having its terminal ends pivotally engaging one of the leg frames, said bar cooperating with an adjacent portion of the said leg frame to form an interlock recess therewith for receiving and releasably securing the connector frame to the leg frame when the bar is moved in a predetermined manner of such pivot, the apex portion of the brace frame being releasably secured to the board.

6. The combination including an ironing board, front and rear leg frames pivotally connected to the board to form a support therefor, a brace frame for bracing the board with respect to one of the leg frames, and a connector frame between the leg frames pivotally secured 105 at one of its ends to one of the leg frames and having a cross bar at its other end releasably secured to the other leg frame by said brace frame.

7. The combination including an ironing 115 board hinged to front and rear supporting leg frames, a brace pivoted to the front leg frame and having a cross bar at its rear end for engagement with the rear leg frame, and a swingable brace frame disposed in substantial parallelism 120 with the front leg frame and connected with the rear leg frame for rigidly locking said spacing brace with the rear leg frame, and said brace frame being attached to the board for supporting the same in a horizontal position.

8. The combination including an ironing board hinged to front and rear supporting leg frames, a spacing frame connecting the leg frames, a brace frame pivoted to the rear leg frame and interslidable with and within said 130 spacing frame to cooperate with the rear leg frame to form an interlock for the spacing frame and adapted to releasably connect with means at the rear end of the board to hold the board in a rigid set up position.

9. The combination of an ironing board hinged near its rear end to front and rear supporting leg frames, a leg spacing frame for interlocking connection with a swingable V-shaped brace frame, said V-shaped brace frame being adapted to form 140 a secondary board support and pivoted to the rear supporting leg frame for rigidly locking said spacing frame with respect to the rear supporting leg frame, said brace frame being disposed in substantial parallelism with the front leg frame.

10. In a collapsible ironing table, the combination including an ironing board, front and rear leg frames pivotally connected to the board to form a support therefor, a spacing frame hinged to the front leg frame and having a cross bar at 150

its rear end, said rear leg frame having means for interlockingly receiving said cross bar, a swingable board bracing member pivoted to the rear leg frame for rigidly locking said cross bar in said 5 receiving means, said bracing member being disposed in substantial parallelism with the front leg frame.

11. In a collapsible ironing table, the combination including an ironing board, front and rear leg frames pivotally connected to the board to form a support therefor, a connector frame pivotally connected with the front leg frame and extending rearwardly and having a cross bar at its rear end for interlocking connections with the rear leg 15 frame, a V-shaped leg brace pivotally connected with the rear leg frame and extending upwardly and rearwardly to the board but in front of said cross bar to establish interlocking connections with the board, said V-shaped leg brace having 20 offsets near its pivotal connections for interlocking with said connector frame.

12. In a collapsible ironing table the combination including an ironing board, front and rear leg frames pivotally secured to the board, a brace 25 frame for releasably connecting the rear leg frame to the board, said brace frame having lateral end extensions forming pivot connections with the leg frame, a connector frame for bracing the leg frames with respect to each other and having an 30 offset rear portion for interlocking engagement with said brace frame extensions.

13. In a collapsible ironing table, the combination including an ironing board attached to a substantially V-shaped front leg frame, the upper 35 lateral ends of which form pivotal connections between the board and a substantially upright rear leg frame, a connector brace extending rearwardly from the front leg frame, a second brace swingably secured to said rear leg frame and extending rearwardly and upwardly through said 40 connector brace to interlock the latter between the rear leg frame and the second brace, and for

releasable connection with the board to form a support therefor, said rear leg frame having means abutting against the adjacent end of said connector brace.

14. In a collapsible ironing table the combination including an ironing board, a substantially upright rear leg frame pivotally connected with a cross bar secured to the board, an inclined V-shaped front leg frame having offset extensions at its ends for pivotal connections with said rear leg frame and cross bar, a connector brace extending from said front leg frame for interlocking connection with a brace frame, such brace frame being pivotally connected with said rear leg frame and having extensions adjacent its said pivotal connections for engagement with said connector brace, said brace frame being so disposed at its connections with rear leg frame as to rigidly lock said leg frames and connector brace when the board is in an inclined position and to releasably lock board when the latter is in a horizontal position.

15. In a collapsible ironing table the combination including a substantially upright rear leg frame, an inclined V-shaped front leg frame pivotally connected with respect to said rear leg frame, an ironing board mounted near its rear end on said frames, a connector frame pivotally connected to the front leg frame and extending rearwardly for interlocking connection with the 105 rear leg frame, a substantially V-shaped brace frame pivotally secured to and swingable with respect to the rear leg frame and slideable within the connector frame for interlocking connections therewith, said brace frame being adapted to releasably connect with rear portion of board, and means connected with said rear leg frame and abutting against one end of said connector brace frame for locking the same with respect to rear leg frame when the table is in set up position.
